UNITED STATES PATENT OFFICE.

CHARLES A. MALLORY, OF DANBURY, CONNECTICUT.

MACHINE FOR SCALDING AND STICKING FUR-BATS TO FELT HAT-BODIES.

SPECIFICATION forming part of Letters Patent No. 254,349, dated February 28, 1882.

Application filed January 6, 1882. (No model.)

To all whom it may concern:

Be it known that I, CHARLES A. MALLORY, of Danbury, in the county of Fairfield and State of Connecticut, have invented certain new and useful Improvements relating to Machines for Scalding and Sticking Fur-Bats to Felt Hat-Bodies, of which the following is a specification.

The object of the invention is to facilitate the introduction and removal of the hat-bodies, and to graduate the force with which the hat-bodies are compressed in the machine.

I employ rollers working in such relation to each other that the hat-body, with the fur-bat previously applied thereto and slightly adhering, shall, by the action of the rollers, be turned and manipulated in the presence of heat and moisture, so as to insure the engagement of the several fibers of the fur strongly and properly with the firmer felted body of the hat. My invention provides means whereby the rollers are conveniently moved together and apart and adjusted in various positions, while they are at the same time continuously turned with the proper velocity.

The accompanying drawings form a part of this specification, and represent what I consider the best means of carrying out the invention.

Figure 1 is a plan view of the machine. Fig. 2 is a side elevation of the same, a portion being broken away to better show the parts beyond. Fig. 3 is an end elevation with a part broken away. Fig. 4 is an elevation of the opposite end, the right hand in Fig. 2; and Fig. 5 is a vertical transverse section through the main body, showing the rollers at work treating one or more hats.

Similar letters of reference indicate like parts in all the figures.

A is a case or tank of wood or other suitable material, to be kept partially filled with water at a nearly or quite boiling temperature, the heat being maintained by steam circulated through pipes α , and allowed to escape into the water through small orifices, as will be readily understood.

B, C, and D are ribbed rollers, of wood or other suitable material, revolved all in the same direction and arranged so that the hat-body m ,

having the fur bat properly applied and being properly rolled up in a separate fabric, may be held and revolved in the open-topped space included between the bodies of the rollers. One of the rollers is mounted in movable bearings, with provision for adjustment at greater or less distances from the others, as required for different sizes of the masses or different characters of the material to be treated. The power is applied through a belt, G, from any suitable motor. This belt runs on a pulley, H', keyed on a short shaft, h, which does not extend across the tank A, but simply turns in bearings outside thereof at the end. It carries a gear-wheel, H, which engages with another gear-wheel, I, turning loosely on a stud, i. This gear-wheel I engages with the gear-wheel B' on the shaft of the roller B, and also engages with the gear-wheel C' on the shaft of the roller C, and consequently turns these rollers by the direct force thus imparted. These rollers C and B may be held in fixed bearings. It is important that the lower be thus held, as otherwise elaborate provisions would be necessary to prevent an escape of water at the bearings. The roller D is worked at so high a level that its bearings are always above the water, and no stuffing-boxes or other means of arresting water are required therefor. The bearings of the roller D are in levers E, which are mounted on pivots e, one at each end of the tank A, and are held in the required positions by pinching-nuts F, fitted on screw-studs f, projecting from the ends of the tank. Sufficient slots are formed where the shaft of this roller extends through the ends of the tank. One extended end of the shaft of the roller B carries a pulley, B*. The corresponding extended end of the roller D carries a pulley, D*. A belt, G, of sufficient length applies on both the pulleys B* and D*, and also traverses down under the idle-pulleys K and L, turning on studs mounted at a considerable distance below, all as represented. The stud k on which one of these pulleys K turns is adjustable by ordinary means as a collar and nut in a slot, a', formed in the fixed framing A'.

P are stop-cocks arranged at different levels, by opening one of which at intervals, or leaving it constantly open, the surplus water

received by the condensing of the steam from the pipe *a*, or by any other means, may be discharged, and the surface of the water in the tank *A* kept at the proper level.

5 In operation the several rollers *B*, *C*, and *D* are turned uniformly, and cause, by virtue of their ribbed surfaces and close relations, the required action on the mass *m* to induce the perfect union of the root of each fiber of fur with the outer surface and even with middle of the thickness of the hat-body to which it is applied; but in order to attain this end it is important that the width of the space within the series of rollers be increased and diminished at times. This my invention allows by simply slackening the nuts *F* and changing the positions of the levers *E*, and consequently of the roller *D*, and then again setting the nuts *F* tightly and holding all firmly until a further 20 change is required.

I can shift the position of the roller *D* to extricate the mass *m* without injury in case of any accident. I can shift the position of said roller by the means shown, or by an easy addition, each time the material is to be removed 25 or introduced; but with the rollers arranged as shown this is not necessary.

The lower roller, *C*, is partly immersed in the hot water and continually supplies heat 30 and moisture to the mass *m* being treated. The turning of all the rolls and of the mass *m* subjects the latter at all points to indefinite gentle compressions and partial release from compression. If it be desired that the action be more 35 compressive, the roller *D* must be set nearer the roller *B*. If a contrary effect is desired, the roller *D* must be shifted away from the roller *B*.

Modifications may be made in many of the 40 details without departing from the principle or sacrificing the advantages of the invention. I can apply the power by other means to the train of rollers *B* *C*. I propose in some cases to extend the shaft of the roller *B* and apply 45 the belt *G* to a pulley and loose pulley thereon, retaining the central idle-wheel, *I*, to convey the motion therefrom to the lower roll, *C*. In all

cases I propose to communicate the motion to the movable pulley *D* by the belt *G* through the aid of the pulleys *K* and *L*. The levers *E* *E* may be extended down farther, or not as far, the pivots *e* *e* being always in the proper line, so that the turning of the levers *E* *E* will not materially tighten or slacken the belt *G*. In theory the best position for the pivots *e* *e* 55 is in a line midway between the axes of the idle-pulleys *K* and *L*; but I do not consider it expedient in most cases to extend the levers *E* so far down, as the change in tightness of the belt *G*, when the centers are higher, is too 60 small to be of importance.

I do not claim anything set forth in the patent to Ezra A. Mallory, July 12, 1881, No. 244,271, nor in the several patents to J. T. Waring, George Yule, and P. V. W. Bishop. 65 My invention differs substantially from all of those. It allows the easy introduction and extraction of the hat-body without changing the position of the rollers for the purpose, while allowing a ready and delicate adjustment of 70 the rolls for different sizes or characters of the hat-bodies.

I claim as my invention—

1. The rollers *B* *C* *D*, arranged to leave a constant space in which the hat-body can be 75 introduced and removed, in combination with the levers *E*, adjusting means *F* therefor, pulleys *B** *D**, belt *G*, and pulleys *K* *L*, arranged for joint operation, as herein specified.

2. The rollers *B* *C* *D*, arranged to provide a 80 space at the top in which the hat-body can be introduced and removed, gears *B*' *C*', pulleys *B** *D**, levers *E*, belt *G*, and pulleys *K* *L*, in combination with each other and with the water-tank *A* and steam-pipes *a*, as herein 85 specified.

In testimony whereof I have hereunto set my hand, at Danbury, Connecticut, this 24th day of December, 1881, in the presence of two subscribing witnesses.

CHARLES A. MALLORY.
